US00D889456S

(12) **United States Design Patent** (10) Patent No.: **US D889,456 S**
(45) Date of Patent: ** Jul. 7, 2020

(54) **SMART APPARATUS**

- (71) Applicant: **BEIJING ORION STAR TECHNOLOGY CO., LTD.**, Beijing (CN)
- (72) Inventors: **Hechun Yao**, Beijing (CN); **Xiaoying Liu**, Beijing (CN)
- (73) Assignee: **BEIJING ORION STAR TECHNOLOGY CO., LTD.**, Beijing (CN)

(**) Term: **15 Years**

(21) Appl. No.: **29/681,138**

(22) Filed: **Feb. 22, 2019**

(30) **Foreign Application Priority Data**

- Aug. 24, 2018 (CN) 2018 3 0473125
- (51) LOC (12) Cl. **14-02**
- (52) U.S. Cl. USPC **D14/336; D14/328; D14/129; D14/203.8**
- (58) **Field of Classification Search**
- USPC D14/300, 301, 302, 307, 314, 328, 336, D14/371, 496, 126, 129, 130, 203.1, D14/203.8, 900, 901, 902, 168; D24/186; D20/10, 19; D19/59-61, 113; D21/324, D21/329, 333; D6/308
- CPC G06F 1/16; G06F 1/1601; G06F 1/1605; G06F 1/1613; G06F 1/162; G06F 1/1626; G06F 1/1633; G06F 1/1637; H04M 3/567
- See application file for complete search history.

(57) **CLAIM**

The ornamental design for a smart apparatus, as shown and described.

DESCRIPTION

FIG. 1 is a front elevation view of a smart apparatus showing my new design;

FIG. 2 is a rear elevation view of thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a first perspective view thereof; and,

FIG. 8 is a second perspective view thereof.

1 Claim, 4 Drawing Sheets
